UNITED STATES PATENT OFFICE.

ARTHUR L. GARNISS, OF SPRINGFIELD, MASSACHUSETTS, ASSIGNOR TO DENNISON MANUFACTURING COMPANY, OF FRAMINGHAM, MASSACHUSETTS, A CORPORATION OF MASSACHUSETTS.

DISPLAY CASE.

Application filed October 24, 1927. Serial No. 228,122.

This invention relates to an improved container for shipping and storing articles and for displaying the same.

The invention has as one object the provision of a container which is adapted not only to hold articles during shippage and storage, but is also arranged conveniently to provide an attractive and pleasing container for articles on display in store windows, on counters, etc. To this end, one element of the container is preferably arranged so that it will fold downwardly and outwardly to form a support for the same, and to expose the contents thereof. Preferably this portion of the box may be provided with suitable indicia or insignia which will be exposed when the container is open and which may enhance the aesthetic appeal of the same while coming to the attention of any one interested in the contents of the container.

This container or display box is particularly designed to be manufactured by machinery and processes commonly known and used in the box-making trade, and its various component elements in general are similar to those which are common in the manufacture of boxes, being combined, however, in a novel relationship to permit the advantageous results referred to above, as well as other advantages which will be apparent to those skilled in the art upon a reading of the subjoined description or claims.

These and other objects of the invention are set forth in the following specification, and in the drawings which form a part thereof, and in which:

Fig. 1 is a front elevation of the container in its closed position;

Fig. 2 is a front elevation of the container in the open position;

Fig. 3 is a sectional view taken along the line 3-3 of Fig. 1;

Fig. 4 is a transverse section taken along the line 4-4 of Fig. 1;

Fig. 5 is a side elevation of the container in open position;

Fig. 6 is a transverse section taken along the line 6-6 of Fig. 2;

Fig. 7 is a sectional view illustrating the top piece of the container partially raised;

Fig. 8 is a view similar to Fig. 7 on a larger scale showing the top piece at right angles to the top wall of the body portion;

Fig. 9 is a sectional view of a portion of the container illustrating the inner section of the front wall in its open position; and

Fig. 10 is a detail view illustrating one manner of hingedly joining the sections of the front wall.

The container embodying the form of the invention selected for illustration in the drawings comprises a formed body portion and a front wall made up of two hingedly joined sections, the inner section being hinged to the body portion, which wall when the contents of the container are to be disclosed upon a counter can be turned on its hinges, the outer section forming a surface upon which the body portion of the container is supported in a vertical position, and the inner surface extending in front of the body portion to provide a surface which bears any desired insignia and displays it to the view of the public.

The reference numeral 20 is employed to designate generally the container which comprises a formed body portion 21 and a movable front wall 22. The body consists of a case 25, a top piece 26 and a base 27. The case 25 has a back wall 30, side walls 31, 32, a bottom wall 33, and a top wall 34. The top piece 26 is provided with side flanges 36 and a front flange 37 and may be hingedly secured to the case 25 in any desired manner. As here illustrated, the top piece 26 is hinged to the top wall 34 by means of a strap 38 (see Fig. 8). The base 27 is secured to the case 25, and provided with flanges 39 which surrounds the lower end of the case. The case 25, top piece 26 and base 27 are each separately formed and covered in any desired manner, preferably by machines and processes well known to the box-making art.

The open face of the body portion is closed during shipment by the movable front wall 22. This wall, in the closing position,

protects the contents of the container, but in the open position discloses the contents so that they may be inspected. The front wall 22 of the embodiment here shown is made up of an inner section 40 and an outer section 41 hinged together in any suitable manner. In the present embodiment, as shown in Fig. 10, the sections 40 and 41 are connected by a flexible hinge 42, which, in order to enhance the appearance of the container is concealed under the cover paper 43. The inner section 40 may be hinged to the front flange 39 of the base 27 by means of a strap 44 as shown particularly in Fig. 9. Within the body portion 21 may be provided supports 50 of any desired form for the purpose of securing the contents of the container in position. In the drawing are shown within the container a pair of shakers 20 A braced at the base by a slotted platform 51 and separated by a partition 52. In order to protect further the surface of the shakers a fabric lining 53 is provided within the container (see particularly Figs. 2, 4 and 6).

It will be noted that the front wall 22 is movable and when turned on its hinges 42, 44, into the position shown in Figs. 2, 6, the contents of the container are entirely protected. The front wall may be held in this closed position by any desired means as for instance by the top piece 26. When the front wall is to be closed the top piece is raised (see Fig. 7) and after the wall has been placed in the position shown in Fig. 3 the top piece is allowed to return to its former position, the front flange 37 extending in front of and confining the upper edge of the front wall.

When the container is to be opened to display the contents, the front wall 22 is preferably swung into the position shown in Figs. 5 and 6. The outer section 41 is turned on the hinge 42 so that it projects below the base 27 of the container and forms a surface on which the body portion 21 of the container is supported in the vertical position, thus exposing the entire contents of the container. The inner section 40 will then lie in front of the body portion and will provide an inclined surface which may bear any suitable insignia or indicia 55 to be displayed in conjunction with the goods such as the name or mark of the manufacturer. With the parts in the position thus described, it is obvious that any one interested in observing the contents of the container will necessarily notice the insignia 55 on the inclined surface provided by the section 40 of the front wall.

Thus the movable front wall not only protects the contents of the container during shipment, but, when the contents are to be displayed, forms both a support for the body portion of the container and also a

surface upon which any desired insignia may be conspicuously brought to the attention of any interested person.

The embodiment here shown and described was selected for the purpose of illustration, not of limitation, and applicant is not limited thereto since it is obvious that other embodiments may be made without departing from the spirit and scope of the invention as set forth in the following claims. 75 75

I claim:

1. A container comprising a formed body portion consisting of a case having back, side, bottom and top walls, a base secured to said bottom wall, and a top piece hinged to said top wall and having side and front flanges, and a front wall hinged to the base of said body portion, and made up of two hingedly joined sections, the inner section being secured to said base and the outer section being free, whereby said front wall in one position closes said container and in the other position opens said container disclosing the contents thereof, said front wall being held closed by the flange of said top piece and when in the open position the outer section of said wall forms a surface on which said body portion is supported vertically and inner section forms a surface in front of said base upon which any desired insignia may be displayed. 80 85 90

2. A container comprising a formed body portion and a front wall hinged at the bottom to said body portion, and made up of an outer section and an inner section hinged together, said front wall, when said container is open, being turned on its hinges so that the outer section forms a surface on which said body portion is supported vertically and the inner section extends in front of said body portion forming a surface upon which any insignia may be displayed. 100 105

3. A container comprising a formed body portion including a case having, back, side, bottom and top walls, and a base secured to said bottom wall, a front wall hinged to said base and made of hingedly joined sections, said front wall in one position closing said container and in another position opening said container and forming a flat surface on which said body portion is supported in the vertical position and an inclined surface in front of said base on which any desired insignia may be displayed and means for securing said front wall in the first-named position. 110 115 120

4. In a container, a front wall comprising an inner section and an outer section hingedly joined, said inner section being hinged to the body portion of the container, said front wall, when said container is open, being turned on its hinges so that the outer section forms a surface on which the body portion is supported vertically and the inner section extends in front of the body 125 130

portion providing a surface upon which any desired insignia may be displayed.

5. In a container, a front wall comprising an inner section and an outer section hingedly joined, said inner section being hinged to the body portion of the container, said front wall, when said container is open, being turned on its hinges so that the outer section forms a surface on which the body

portion is supported vertically and the inner section extends forwardly and downwardly in front of the body portion providing an inclined surface upon which any desired insignia may be displayed. 10

Signed by me at Springfield, Mass., this 11th day of September, 1927.

ARTHUR L. GARNISS.
